(21) Appl. No.: **29/132,886**

CLAIM

(22) Filed: **Nov. 17, 2000**

The ornamental design for a vibrating child pager and transmitter, as shown and described.

(51) LOC (7) Cl. **14-03**

DESCRIPTION

(52) U.S. Cl. **D14/191**

FIG. 1 is a front elevational view of the vibrating child pager and transmitter of the present invention;

(58) Field of Search D10/104, 106;
D14/155, 191, 192, 299; 340/311.1, 349,
351, 570-573; 455/90, 92, 100, 344

FIG. 2 is a bottom elevational view of the vibrating child pager and transmitter of FIG. 1;

(56) **References Cited**

FIG. 3 is a rear elevational view of the vibrating child pager and transmitter of FIG. 1;

U.S. PATENT DOCUMENTS

FIG. 4 is a top plan view of the vibrating child pager and transmitter of FIG. 1;
